ROCKWELL L. GALLUP AND WALTER G. WACHS, OF CHICAGO, ILLINOIS, ASSIGNORS TO BARRY-WEHMILLER MACHINERY COMPANY, OF ST. LOUIS, MISSOURI, A CORPORATION OF MISSOURI.

BOTTLE-WASHING MACHINE.

1,273,604.

Specification of Letters Patent. Patented July 23, 1918.

Original application filed September 19, 1914, Serial No. 862,476. Divided and this application filed October 27, 1917. Serial No. 198,751.

To all whom it may concern:

Be it known that we, ROCKWELL L. GALLUP and WALTER G. WACHS, citizens of the United States, both residing at Chicago, in the county of Cook and State of Illinois, have jointly invented certain new and useful Improvements in Bottle-Washing Machines, of which the following is a specification.

This invention relates to bottle washing machines and more particularly to mechanism for receiving and conveying bottles therefrom, this application being a division of our application Serial No. 862,476 filed September 19, 1914, for improvements in bottle washing machines.

The object of our invention is the provision of means for automatically removing the bottles after the washing operation is completed and conveying them to some desirable point as, for example, to a bottling machine which may be arranged to receive the bottles as fast as they are washed and to fill them at once.

More specifically our object is to prevent overturning of the bottles as they are delivered to a moving belt conveyer.

Further objects and advantages of our invention will be apparent as it is better understood by reference to the following specification when read in connection with the accompanying drawing illustrating the preferred embodiment thereof, in which—

Figure 1 is a sectional view of a portion of the machine illustrating our mechanism in plan;

Fig. 2 is a section on the line 2—2 of Fig. 1;

Fig. 3 is a sectional view through a portion of the machine illustrating the mechanism in section;

Fig. 4 is an end elevation of a portion of the mechanism.

Referring to the drawing 5 (Fig. 3) indicates a portion of the frame of the machine in which a shaft 6 is mounted. Sprockets 7 on the shaft 6 support a conveyer 8 which carries the bottles through the machine. The conveyer is provided at intervals with cup shaped members 9 to engage the bottles, and is intermittently actuated in any suitable manner.

Mounted on the frame 5 at the discharge end of the machine are a pair of brackets 10 supporting the automatic means for re-

moving bottles from the machine. A base 55 plate 11 extends between the brackets. A side plate 12 having a beveled nose 13 and a slotted plate 14 having a lining 15 of fiber or other suitable material are similarly mounted forming a trough. An endless belt 60 16 extends along the base 11 over pulleys 17 and 18 (Fig. 2) at either end of the base plate 11. The belt 16 is driven from any suitable source of power through bevel gears 19 and 20 (Fig. 1) and a pulley 21. 65

A rock shaft 22 is mounted in the brackets 10 and is provided with a plurality of arms 23 secured thereto and each carrying a blade 24 adapted to enter the slots in the plate 14. A lever 25 is secured to one end of the rock 70 shaft 22 and is connected by a rod 26 to an intermittently actuated member (not shown) preferably the member which actuates the sprockets 7 to advance the conveyer 8. At its opposite end the rock shaft 22 is provided with a lever 27 connected to the frame 1 by a tension spring 28 which normally draws the lever 27 toward the frame 1 and hold the blades 24 in the position indicated in Figs. 3 and 4. 75

Through the rod 26 the lever 25 is swung to the right viewing Fig. 4 as the conveyer 8 is advanced, thus moving the blades 24 through the slots in the plate 14 forming compartments above the belt 16 to receive 80 the bottles. The blades 24 are provided at their lower edges with a portion 29 (Fig. 1) bent in a direction opposite to the direction of movement of the belt 16. This portion engages the bottles near their bottoms as 85 the belt moves them against the blades and prevents over-turning of the bottles. To insure movement of the bottles into the proper compartments we provide guides 30 (Fig. 3) on a transversely extending rock shaft 31. 90 Cam levers 32 secured to the rock shaft 31 are disposed in the path of cam plates 33 on the conveyer 8 so that after the bottles are discharged the shaft 31 is rocked and consequently the guides 30 are lifted sufficiently 95 to permit the cup shaped members 9 on the conveyer 8 to pass.

The operation of the mechanism will be readily understood from the following brief description thereof. The bottles having 105 been subjected to the cleaning operation in the washing machine are carried by the conveyer 8 to the delivery end of the machine.

As the cup shaped members 9 approach the point indicated in Fig. 3 the blades 24 are moved inwardly and positioned above the belt 16 forming compartments to receive the bottles. The bottles pass through the guides 30 into the compartments and rest in upright position with their bottoms on the belt 16. The portions 29 of the blades prevent overturning of the bottles. The blades 24 are then withdrawn and the bottles are carried by the belt 16 to any convenient point as for example to a bottle filling machine not shown. The belt 16 is timed to move all of the bottles delivered at each intermittent advance of the conveyer 8 out of the machine. The filling machine may be timed to run slightly faster than the washing machine so that the bottles are filled as fast as washed without being handled by the workmen.

While we have described a constantly moving belt for removing the bottles and this is the preferred embodiment of our invention it is obvious that an intermittent moving belt may be substituted therefor.

From the foregoing it will be apparent that we have provided a mechanism for automatically removing bottles from a washing machine and carrying them to a desired point. By the use of our mechanism the bottles may be automatically delivered at the filling machine as rapidly as they are cleaned.

It is to be understood that the mechanism described and claimed in the present application is adapted to be applied to various forms of bottle washing machines which soak, brush or otherwise treat the bottles and it is to be further understood that various changes may be made in the form, construction and arrangement of the parts without departing from the spirit and scope of the invention or sacrificing any of its material advantages, the form hereinbefore described being merely a preferred embodiment thereof.

We claim:

1. In a bottle washing machine, the combination of a conveyer for carrying bottles through the machine, a carrier disposed adjacent the discharge end of said conveyer and extending transversely thereof for automatically removing bottles from the machine, and means adapted to be alternately positioned above said carrier before the bottles are delivered thereto to form a plurality of compartments arranged longitudinally of said carrier and to prevent the bottles from over-turning as they are discharged thereupon, and withdrawn to permit the bottles to advance with said carrier.

2. In a bottle washing machine, the combination of a conveyer for carrying bottles through the machine, a carrier disposed adjacent the discharge end of said conveyer

and extending transversely thereof for automatically removing bottles from the machine, and a plurality of blades adapted to be alternately positioned above said carrier before the bottles are delivered thereto to prevent the bottles from over-turning as they are discharged thereupon, and withdrawn to permit the bottles to advance with said carrier.

3. In a bottle washing machine, the combination of a conveyer for carrying bottles through the machine, an endless carrier disposed adjacent the discharge end of said conveyer and extending transversely thereof for automatically removing bottles from the machine, means for continuously moving said carrier, and a plurality of pivotally mounted blades adapted to be alternately positioned above said carrier before the bottles are delivered thereto to form a plurality of compartments, whereby the bottles are prevented from overturning as they are discharged upon said carrier and withdrawn to permit the bottles to advance with said carrier.

4. In a bottle washing machine, the combination of a conveyer for carrying bottles through the machine, an endless belt disposed adjacent the discharge end of said conveyer and extending transversely thereof for automatically removing the bottles from the machine, means for constantly moving said belt, a plurality of blades pivotally mounted adjacent said carrier, and means for alternately moving said blades to a position above said belt before the bottles are delivered thereto to form a plurality of compartments arranged longitudinally thereof, whereby the bottles are prevented from overturning as they are discharged upon said carrier and withdrawing said blades to permit the bottles to advance with said carrier.

5. In a bottle washing machine, the combination of a conveyer for carrying bottles through the machine, a carrier disposed adjacent the discharge end of said conveyer and extending transversely thereof for automatically removing the bottles from the machine, means for moving said carrier, a plurality of blades pivotally mounted adjacent said carrier, means for normally holding said blades in inoperative position, and means for alternately moving said blades to a position above said carrier before the bottles are delivered thereto to form a plurality of compartments, arranged longitudinally thereof, whereby the bottles are prevented from overturning as they are discharged upon said carrier, and withdrawing said blades to permit the bottles to advance with said carrier.

6. In a bottle washing machine, a constantly moving carrier for automatically removing bottles from the machine, and a plurality of blades adapted to be intermittently

positioned above said carrier, the bottom of said blades being off set in a direction opposite to the direction of movement of said carrier, whereby said blades engage the 5 bottle adjacent their bottoms and overturning of the bottles is prevented.

7. In a bottle washing machine, the combination of a conveyer for carrying bottles through the machine, a carrier disposed adjacent the discharge end of the conveyer and extending transversely thereof for automatically moving the bottles from the machine, guides to direct the bottles to said carrier, and means in front of and beneath 10 said guides adapted to be alternately positioned above said carrier to prevent overturning of the bottles, when delivered thereto, and withdrawn to permit the bottles to advance with said carrier.

20 8. In a bottle washing machine, the combination of a conveyer for carrying bottles through the machine, a carrier disposed adjacent the discharge end of the conveyer and extending transversely thereof for automatically removing the bottles from the machine, guides to direct the bottles to said carrier, a plurality of pivoted blades in front of and beneath said guides, and means for 25 positioning said blades above said carrier prior to delivery of the bottles thereto, and withdrawing said blades after delivery of the bottles to permit the latter to advance with said carrier.

30 9. In a bottle washing machine the combination of a conveyer for carrying bottles through the machine, a carrier disposed adjacent the discharge end of the conveyer and extending transversely thereof for automatically removing bottles from the machine, 35 guides to direct the bottles to said carrier a plurality of pivoted blades and means for 40

positioning said blades above said carrier prior to delivery of bottles thereto, the bottoms of said blades being offset in a direction opposite the direction of movement of said 45 carrier whereby said blades engage the bottles adjacent their bottoms and overturning of the bottles is prevented.

10. In a bottle washing machine the combination of a trough, a constantly moving 50 carrier on said trough, a plurality of blades movable through slots in the side of said trough to form a plurality of pockets above said carrier, and means for delivering a plurality of bottles simultaneously to said 55 pockets.

11. In a bottle washing machine the combination of a trough, a constantly moving carrier in said trough, a plurality of blades movable through slots in the side of said 60 trough to form a plurality of pockets above said carrier, and means for delivering a plurality of bottles simultaneously to said pockets, the bottoms of said blades being offset in a direction opposite the direction of 65 movement of said carrier whereby said blades engage the bottles adjacent the bottoms and overturning of the bottles is prevented.

12. In a bottle washing machine the combination of a trough, a constantly moving carrier in said trough, a plurality of blades mounted for simultaneous movement to and from a position in said trough above said carrier thereby forming a plurality of pockets and means for delivering a plurality of 70 bottles to said pockets. 75
